(57) **CLAIM**

The ornamental design for a stroller attachment, as shown and described.

DESCRIPTION

FIG. 1 is a front perspective view showing the stroller attachment embodying the new design;

FIG. 2 is a rear perspective view showing the stroller attachment embodying the new design;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof;

FIG. 8 is a rear elevation view thereof;

FIG. 9 is a front perspective view showing a variation of the stroller attachment design;

FIG. 10 is a front perspective view showing a variation of the stroller attachment design;

FIG. 11 is a rear perspective view thereof;

FIG. 12 is a top plan view thereof;

FIG. 13 is a bottom plan view thereof;

FIG. 14 is a right side elevation view thereof;

FIG. 15 is a left side elevation view thereof;

FIG. 16 is a front elevation view thereof;

FIG. 17 is a rear elevation view thereof; and,

FIG. 18 is a front perspective view showing a variation of the stroller attachment design.

The broken lines in the drawing views are included for the purpose of illustrating unclaimed environment only, and forms no part of the claimed design.
